(57) **CLAIM**

The ornamental design for an automated teller machine, substantially as shown and described.

DESCRIPTION

FIG. 1 is a perspective view.

FIG. 2 is a front view.

FIG. 3 is a rear view.

FIG. 4 is a left side view.

FIG. 5 is a right side view.

FIG. 6 is a top view; and,

FIG. 7 is a bottom view.

The structural elements shown in broken lines form no part of the claimed design.

1 Claim, 5 Drawing Sheets

FIG. 1

FIG. 2**FIG. 3****FIG. 4**

FIG. 5

FIG. 6

FIG. 7
